(57) **CLAIM**

We claim the ornamental design for a sash lock, as shown and described.

DESCRIPTION

FIG. 1 is a perspective view of a sash lock showing my new design;

FIG. 2 is a front view thereof;

FIG. 3 is a top plan view thereof;

FIG. 4 is a bottom plan view thereof;

FIG. 5 is an end view thereof;

FIG. 6 is the opposite end of FIG. 5; and,

FIG. 7 is a rear view of FIG. 1.

The ornamental design which is claimed is shown in solid lines in the drawings. The broken lines in the drawings are for illustrative purposes only and form no part of the claimed design.
